T. E. McGAUGHEY

ALBUM FOR PHOTOGRAPHS

Filed Nov. 3, 1922

FIG. 1.

FIG. 2.

G. J. Baker

WITNESS:

T. E. McGaughey
INVENTOR
BY Victor J. Evans
ATTORNEY

UNITED STATES PATENT OFFICE.

THOMAS E. McGAUGHEY, OF NEW BEDFORD, MASSACHUSETTS.

ALBUM FOR PHOTOGRAPHS.

Application filed November 3, 1922. Serial No. 598,849.

To all whom it may concern:

Be it known that I, THOMAS E. McGAUGHEY, a citizen of the United States, residing at New Bedford, in the county of Bristol 5 and State of Massachusetts, have invented new and useful Improvements in Albums for Photographs, of which the following is a specification.

This invention relates to an album for 10 photographs, the general object of the invention being to provide each leaf of the album with a space for receiving a photograph and other spaces for receiving data as to when and where the photograph was 15 taken and remarks concerning the same.

Another object of the invention is to recess each leaf at the place where the photograph is to be placed with the edges around 20 the recess gummed to engage two edges of the photograph.

This invention also consists in certain other features of construction and in the combination and arrangement of the several parts, to be hereinafter fully described, illustrated in the accompanying drawings and 25 specifically pointed out in the appended claim.

In describing my invention in detail, reference will be had to the accompanying 30 drawings wherein like characters denote like or corresponding parts throughout the several views, and in which:—

Figure 1 is a view showing the album in open position.

Figure 2 is a view of one of the pages thereof with the photograph.

As shown in these views each page 1 of the album is provided with a recess 2 in its upper right-hand corner, the edges of the

page adjacent the recess being gummed, as 40 at 3, so that one side edge and an end edge of the photograph 4 may be connected with the page. The photograph will then cover the recess. Each page has printed or otherwise placed thereon the words "Taken at," 45 "Date" and "Memo." so that the page can receive data indicating where the photograph was taken, the date and any remarks relating to the same. By recessing the page where the photograph is attached it will 50 prevent the photographs from making the album bulky as is the case where the photograph is placed directly upon the page. By recessing the pages the pages will be of the same thickness throughout with the exception of the overlapping edges of the photograph and page.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

An album of the class described having each page provided with a recess formed by cutting away one of the outer corners of the page and adhesive material placed on 70 the page adjacent the recess so that a photograph can have its overlapping edges fastened to the page when the photograph is placed over the recess.

In testimony whereof I affix my signature.

THOMAS E. McGAUGHEY.
